CLAIM

The ornamental design for a facsimile machine, as
shown and described.

DESCRIPTION

FIG. 1 is an upper frontal perspective view of the fac-
simile machine showing my new design;

FIG. 2 is a front elevational view thereof;

FIG. 3 is a right side elevational view thereof, the left
side being a mirror image;

FIG. 4 is a rear elevational view thereof;

FIG. 5 is a top plan view thereof; and,

FIG. 6 is a bottom plan view.
